MACHINE FOR PLANE GRINDING
PISTON RINGS

Emil Junker, Zurich, Switzerland

Application August 30, 1934, Serial No. 742,185
In Germany September 7, 1933

1 Claim. (Cl. 51—112)

The present invention relates to an improved means for the mass production of piston rings and more particularly to a device for the machining of the piston rings.

5 The main object of the invention is to provide an improved automatic machine for the finishing of the ring side faces by grinding and honing to obtain a good finish and perfect accuracy.

It has been proposed to use a double disc 10 grinding machine for simultaneously grinding both the side faces of the piston rings. The machines used for such purpose have the disadvantage that the piston rings have had to sustain a certain strain which led to distortion.

15 It is an object of the present machine to obviate the disadvantages of the previous machines in that the piston rings are passed uniformly between the two inclined grinding discs free from pressure and tension, without the piston 20 rings coming into contact with one another.

I obtain the said object by feeding the piston rings by an endless band which is drawn between the two discs and which is provided with openings in which the piston rings are located 25 free from tension.

The feeding speed can be adjusted by varying the speed of the band. The piston rings are accurately guided in front of and beyond the grinding discs between rails so that the piston 30 rings are not damaged by the grinding discs when entering and leaving.

An example of construction of the subject of the invention is shown diagrammatically in the accompanying drawings, wherein:

35 Fig. 1 shows the lay-out of the machine in plan;

Fig. 2 is a cross-section on the line A—B of Fig. 1;

Figs. 3 and 4 show a plan and longitudinal 40 section of the carrier-band for the piston rings.

Fig. 5 shows in sectional elevation the device for inserting the piston rings into openings of the endless band;

Figs. 6 and 7 are sections on lines C—D and 45 E—F of Fig. 5, respectively.

In a frame 23 two grinding discs 1 and 2 are secured to spindles 3 and 4 respectively. The latter run in the bearings 5, 6 and 7, 8 of the frame 23. Separate motors 9 and 10 drive the 50 grinding spindles 3 and 4 through elastic clutches 11 and 12. Between the grinding discs 1 and 2 is passed an endless band 13 for instance of hardened steel, which serves as a carrier of the piston rings 18 and which runs in the direction of the arrow I. The band 13 passes over three roll-

ers 15, 16, 17 of which at least one is driven by a motor not shown in the drawing. The band 13 is provided with openings 24 which are sufficiently large to receive each a piston ring 18 to be treated, the piston ring resting loosely in the 5 opening without pressure and thus without tension. The thickness of the band 13 is less than the width of the piston rings 18 to be treated, which is about two millimeters, the band itself therefore is not ground when passing between 10 the grinding discs 1 and 2. The piston rings 18 are placed into the band 13 by means of a device for automatically feeding the same. Directly adjacent the grinding discs 1 and 2 are provided guide rails 19, 20 for the entrance and 15 21, 22 for the outward passage of the piston rings 18. These guide rails lead each piston ring 18 accurately between the discs 1 and 2 so that the latter cannot damage the rings. The spindles of the discs 1 and 2 are placed at an angle to 20 each other so that the working faces of the discs are not parallel to one another but are more or less inclined relatively to one another in accordance with the layer to be ground off by the discs 1 and 2. The piston rings 18 are brought between the working faces of the discs where the gap between them is wider. The movement of the band is kept as uniform as possible in order to maintain the feed of the rings to the operative position uniform. 30

To insert a piston ring 18 in the openings 24 the feeding device shown in Figs. 5, 6 and 7 is used. The device comprises a support 25 and a vertical wall 33. The set of piston rings 18 rests on a slanting face of the support 25 and on the 35 vertical face of the wall 33. A plate 28 sliding on a bar 34 pushes the set of piston rings 18 against the endless band 13. To the plate 28 the one end of a belt 29 is fixed. The belt runs 40 over a pulley 30 and carries a weight 31. The latter exerts a constant pressure on the pile of piston rings 18. While the band 13 passes in front of the pile, the piston rings are inserted one by one in the openings 24. The piston rings 45 are pressed against the adjustable plate 19 and are passed between the plates 19, 20 to the grinding discs 1, 2. Care is being taken that the gap between the plates 19, 20 coincides exactly with the gap between the discs 1, 2 both the plates 50 19 and 20 being adjustably mounted by some well known means. The band 13 slides over the faces of guide bars 26, 27, and it runs in a vertical plane at the centre of the gap.

It will be seen that the weight 35 sustained 55

by the cord 36 passing over pulley 37 adjusts the roller 15 to keep the band taut.

Having now particularly described and ascertained the nature of my said invention and in 5 what manner the same is to be performed, I declare that what I claim is:—

In a machine for grinding and honing piston rings and the like, two rotary grinding discs rotatable on axes located in a horizontal plane, 10 a thin flexible endless band passing between said

grinding discs approximately parallel to the faces thereof, a set of guide rollers around which said band is passed, the axes of said rollers lying normal to said horizontal plane, said band having openings through the same loosely to receive the rings to be ground and completely to encircle the rings and being of less thickness than that of the rings, and means to maintain said band constantly under tension. 5

E. JUNKER. 10
